UNITED STATES PATENT OFFICE.

FRED H. DANIELS, OF WORCESTER, MASSACHUSETTS.

GUARD-SCREEN FOR ROLLING-MILLS.

SPECIFICATION forming part of Letters Patent No. 367,193, dated July 26, 1867.

Application filed December 2, 1866. Serial No. 220,462. (No model.)

To all whom it may concern:

Be it known that I, FRED H. DANIELS, a citizen of the United States, residing at Worcester, in the county of Worcester and State of Massachusetts, have invented certain new and useful Improvements in Guard-Screens for Rolling-Mills, of which the following, together with the accompanying drawings, is a specification sufficiently full, clear, and exact to enable persons skilled in the art to which this invention appertains to make and use the same.

In wire-rod-rolling mills constructed for operating on the "continuous" system, and especially in those adapted for reducing the rods to a small size, the latter rolls in the train—those near to and including the final or finishing rolls—require to run at a high rate of speed, and the rod is projected forward with a great velocity.

Owing to conditions of quality and defects or flaws in the metal worked, or by displacement or derangement in the adjustment of the guides or rolls, it often occurs that the passage of the rod becomes obstructed and the rod overflows or accidentally breaks out at some intermediate portion of the mill in a loose end or flying loop, and in case of such "break-out" or accident, the probability of which proportionally increases with the increase of speed of the rolls, the escaping overflow or break-out of the rod is liable to be thrown in any unexpected direction and with the force of a projectile; hence the attendants deem it unsafe to stand near the latter part of a mill which is run beyond a moderate limit of speed.

The object of my present invention is to provide means for confining the overflow or broken-out or flying loop of rod and for protecting the attendants from liability to injury, while affording facilities for observing the operation of the mill while the guard is in position, allowing quick and convenient access to the rolls and guides and ready removal for permitting the clearing of the train from "cobbles" or tangled rod when required.

To this end my invention consists in a guard or screen constructed and adapted for use in combination with the rolling-mill, as hereinafter more fully explained, the particular subject-matter claimed being hereinafter definitely specified.

In the drawings, Figure 1 is a front view of the latter portion of a continuous-rolling mill, showing my invention applied thereto. Fig. 55 52 is a transverse section at the position of line *x*, and Fig. 3 is a horizontal section or plan view of the same.

Referring to parts, A denotes the rolling-mill, which may be a continuous mill of ordinary construction, and comprising, say, fourteen to twenty pairs of rolls, more or less. At the latter end of the train I arrange a shield or plate of metal, B, preferably curved around the end of the mill, and also arched forward at the top. Said shield or plate is provided with a foot or flange, through which I arrange bolts *b*, for securing it rigidly in position.

The spaces or openings for the bolts are slotted in from the rear edge of the flange, so that the shield can be released by moving it forward, without the necessity of fully unscrewing the bolts. The delivery-guide G passes through an opening in the shield or plate B. 70 Adjacent to the end guard or shield, B, and extending along parallel with the front of the machine, and at a distance of about twenty inches (more or less) therefrom, I arrange an open-work screen or screens, C, the top of 75 which is made rearwardly overhanging or arched, in the manner substantially as indicated in Fig. 2, to cover and inclose the rolls and roll-housings of the mill, so that a broken-out end or flying loop of rod, if accidentally 80 thrown out from the mill, will be interrupted and confined within the limit of the screen.

Along the front of the screen C, at positions corresponding with the guides or rolls, I arrange doors D, or movable portions of screen, 90 which open and permit access through the screen to the roll-journals and bearings, and also to the intermediate guides between the several pairs of rolls. In the present instance the doors D are shown in a continuous series along 95 the entire front of the screen; but a greater or less number might be used. Two sections of screen C are herein shown; but a screen or guard of one, two, three, or more sections, as desired, may be employed in connection with 100 an end guard or shield, which latter is in the present instance made as a solid plate, or unperforated; but said shield might, if desired, be perforated or made of strong wire-netting.

I prefer, however, to form it as shown. The sections of screen C are preferably made of such height that a man can walk along the space between the mill and front of the screen beneath the arch or overhanging top when the mill is not running.

The doors or such portions of the screen as are desired to be opened or removed may, if preferred, be arranged to swing upward or outward from the mill, or may be arranged to slide longitudinally on suitable trucks or guides, or in other convenient manner, so that space can be opened to allow ready access to such portions of the mill as may require attention.

The foot of the screen is preferably secured to the floor by detachable connections i, and the several sections of screen are connected by chains E, or equivalent means, with a counter-balancing-weight or with a suitable hoisting-drum, F, whereby the screens can at any time desired be raised or hoisted up clear of the mill, thus leaving an open and unobstructed space for the convenience of clearing away 25 cobbles or break-outs of rod, or for removing and replacing rolls, guides, or housings, or making any kind of repairs on the mill, and thereafter quickly replaced in position by lowering it again into place.

30 What I claim as of my invention, and desire to secure by Letters Patent, is—

1. In combination with a wire-rod-rolling mill, a metal or woven-wire guard-screen adapted to inclose the high-speeded portion of 35 the mill, for confining accidental outflow or broken-out rods and wholly or in part removable to permit ready access to the mill.

2. A perforated or netted screen having an overhanging top and a series of doors, D, substantially as and for the purpose set forth.

3. The combination, with a continuous wire-rod-rolling mill, of a screen formed of netting

or perforated metal, with an upright portion extending along in front of the mill, and an overhanging top inclosing the rolls and roll-housings, substantially as and for the purpose set forth.

4. The combination, with a continuous wire-rod-rolling mill, of a transversely-disposed guard, as B, at the end of the mill, and a 50 guard or series of guard-sections extending along the front of the mill and overhanging the rolls and roll-housings, substantially as and for the purpose set forth.

5. The combination, with a continuous rolling-mill, of a screen overhanging the rolls and housings at the top of the mill and capable of being raised or swung up to permit access to the machinery, and a supporting device in connection therewith for sustaining the overhanging portion of the screen and for facilitating the raising thereof, for the purpose set forth.

6. The combination, with a continuous wire-rod-rolling mill, of a removable screen of netting or perforated metal, and suspending devices whereby said screen is supported from above, and an elevating device to facilitate raising said screen away from the mill and lowering it into place, substantially as and for 70 the purpose set forth.

7. The combination, with a continuous wire-rod-rolling mill, of a guard or screen arranged along the front of the mill and provided with doors or movable portions at positions corresponding with the respective guides or roll-journals, for permitting ready access to the same, substantially as set forth.

Witness my hand this 30th day of November, A. D. 1886.

FRED H. DANIELS.
